(57) **CLAIM**

The ornamental design for an LED display module, as shown and described.

DESCRIPTION

FIG. 1 is a front perspective view of an LED display module showing my new design; according to one embodiment of the present invention;

FIG. 2 is a front view thereof;

FIG. 3 is a rear view thereof;

FIG. 4 is a side view thereof;

FIG. 5 is a top view thereof; and,

FIG. 6 is a rear perspective view thereof.

The broken lines in the drawing are for the purpose of illustrating portions of the LED display module and form no part of the claimed design.
